CLAIM

The ornamental design for a laryngoscope blade, as shown and described.

DESCRIPTION

FIG. 1 is a bottom, left side perspective view of a laryngoscope blade showing my new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a front elevational view thereof; and,

FIG. 7 is a rear elevational view thereof.

The broken lines in FIGS. 1, 6 and 7 represent environmental structure and form no part of the claimed design.
